UNITED STATES PATENT OFFICE.

DEXTER C. BAKER, OF OAKLAND, CALIFORNIA, ASSIGNOR TO BAKER-HANSEN MANUFACTURING CO., OF ALAMEDA, CALIFORNIA, A CORPORATION OF CALIFORNIA.

AIR COMPRESSOR AND VALVE.

Application filed May 8, 1923. Serial No. 637,437.

To all whom it may concern:

Be it known that I, DEXTER C. BAKER, a citizen of the United States, and a resident of the city of Oakland, in the county of 5 Alameda and State of California, have invented a new and useful Air Compressor and Valve, of which the following is a specification.

This invention relates to an air compressor, and more particularly to the control of the air ports in a reciprocating type 10 compressor.

In such compressors, it is of course necessary to permit air to enter the compression cylinder on the intake stroke of the piston, and to permit the piston to discharge the compressed air on its compression stroke. It has been customary to provide various forms of valves which seat by spring pressure and in which this pressure is temporarily overcome during the proper changes 15 in the cycle of the compressor. Thus during the intake or suction stroke, the intake valve spring is overcome by the suction and permits entry of air to the cylinder. Upon a reversal of movement of the piston, the pressure of the air within the cylinder closes this valve and serves to open the discharge valve leading to an air tank.

In such constructions it has been found 20 that much energy is used up in operating the valves, and it is therefore one of the objects of my invention to make it possible to move the valve parts with little effort, while still insuring accurate seating and proper 25 operation.

It is another object of my invention to improve in general the operation of reciprocating air compressors.

It is still another object of my invention 30 to provide an intake valve construction that ensures a large and quick opening upon the beginning of the suction stroke, and a rapid closure when the piston starts to compress 35 the air drawn in. In this way there is greater certainty that no wire-drawing of the incoming air can result, and the compressor may operate most efficiently and utilize the cylinder volume to its greatest 40 extent.

In order that the compressor operate most 45 successfully, it is advantageous to permit

the piston, in its reciprocations, to travel substantially the full length of the cylinder, so that on compression substantially all of 55 the compressed air may be forced through the discharge valve. I accomplish this highly desirable result by arranging the valves in such a way that they do not occupy any material space within the cylinder. 60

My invention possesses other advantageous features, some of which, with the foregoing, will be set forth at length in the following description, where I shall outline in full that form of the invention which I 65 have selected for illustration in the drawings accompanying and forming part of the present specification. Although I have shown in the drawings but one embodiment 70 of my invention, I do not desire to be limited thereto, since the invention as set forth in the claims may be embodied in other forms also.

Referring to the drawings:

Figure 1 is a sectional view showing the 75 end of a compressor cylinder, in which valves embodying my invention are used;

Fig. 2 is a plan view of the valve plate used in the compressor illustrated in Fig. 1;

Fig. 3 is a sectional view of the plate 80 shown in Fig. 2;

Fig. 4 is a plan view of one form of member adapted to exert a resilient closing force for the intake valve shown in Fig. 1;

Fig. 5 is a plan view of a member which 85 is associated with the intake valve;

Fig. 6 is a plan view of the intake valve, which is arranged to be seated by the member illustrated in Fig. 4; and

Fig. 7 is an enlarged sectional view 90 through the intake valve illustrated in Fig. 1.

A compressor cylinder 11 has a piston 12 which is arranged to be reciprocated therein in any appropriate manner. Since the details of the cylinder, piston, and the source of mechanical power for reciprocating the piston form no part of my present invention, it is considered unnecessary to describe these elements further. It is also evident that as many cylinders and as many stages may be used in a complete air compressor 100 as may be desired. The cylinder head 13 in the present instance serves to provide an

annular intake passageway 14, as well as a circular discharge passageway 15, between which passageways and the interior of the cylinder 11, appropriate valves are provided. The air is led to the passageway 14 from an outside source through the opening 16 (shown dotted in Fig. 1) to this annular passageway, while the pipe fixture 17 serves to conduct the compressed air from the passageway 15.

A valve supporting plate 18 may conveniently be utilized for supporting the valve structure. This valve plate is interposed between the end of cylinder 11 and the head 13, the three parts being securely fastened together as by a plurality of screws 19 which extend through these parts. This plate covers the cylinder end completely, except for a pair of sets of annularly arranged apertures 20 and 21. The set 20 serves to connect the cylinder with the annular intake passageway 14, whenever the intake valve is opened. This valve may comprise a ring 22, shown in greater detail in Fig. 6, which ring serves when it is seated, to cover up all of the apertures 20 and prevent communication between the cylinder 11 and the passageway 14. This valve ring 22 is arranged in an annular groove 23 cut in the plate 18 on the side of the plate nearest the cylinder 11. Furthermore a second narrow groove 24 is cut in the bottom of the groove 23, which narrow groove connects all of the apertures 20. The ring 22 is wide enough to cover up this narrow groove as illustrated most clearly in Fig. 7.

In order that the compressor function properly, it is essential to keep the ring 22 seated over the groove 24 until the suction or intake stroke begins. In order to accomplish this purpose in a highly satisfactory manner and without taking up an appreciable amount of space in the cylinder 11, I provide a very shallow spring cup 25, shown most clearly in Figs. 4 and 7. This cup is made of resilient material, such as phosphor bronze, and its edge 26 is arranged to contact with the ring 22 at or near its outer edge, on a surface substantially co-extensive with the series of intake apertures 20. In order to hold this spring member 25 in proper operative position, a bolt 27 passing through the cup and the plate 18 near their center may be used. The spring cup 25 takes up hardly any useful cylinder volume; at the same time it ensures a substantially even pressure on the ring 22 at all points. This latter feature cannot be too strongly emphasized. Due to this feature, when the suction stroke is started, the valve ring 22 leaves its seat at once, in response to the vacuum thus created, and uncovers all of the apertures 20 substantially simultaneously. There can be no tilting of the ring 22, with attendant danger of wire

drawing of the air as it is sucked in. Furthermore it is possible to drive the piston 12 up close to the cup 23, as shown in Fig. 1, and thus most efficiently to utilize the cylinder volume.

In order to provide a proper support for the cup 25, as well as a stop to limit the opening movement of the valve 22, I prefer to interpose a disc-like member 28 between the spring cup 25 and the plate 18. The 75 edge of this disc extends over the valve 22, and thus prevents it from opening too far. Apertures 29 and 30 are provided in both the cup 25 and disc 28 to leave the discharge passageways 21 unimpeded. Furthermore 80 another series of apertures 31 may be provided in the spring cup 25 in order to ensure against the trapping of any air between the cup 25 and the disc 28, as the cup is flexed and unflexed in the course of its 85 operation.

The series of discharge apertures 21, which are adapted to connect the cylinder 11 with the discharge passageway 15, may be controlled by a spring pressed valve ring 32, on that side of the valve plate 18 which is farthest from the cylinder chamber. This valve ring 32, being directly exposed to the pressure of the air in the discharge passageway, is kept seated thereby, and cannot be 90 unseated until the pressure of the compressed air in the cylinder 12 on its discharge stroke is great enough to accomplish this. Due to this arrangement, it is unnecessary to provide a strong supplementary spring pressure on the valve ring 32. A coiled spring 33 may be utilized for providing this weak pressure. A guide post 34, fastened to the plate 18, as by aid of the bolt 27 before mentioned, provides a flange 100 abutment 35 for the stationary end of the spring. Furthermore a shoulder 36 on the post 34 serves as a stop for preventing the valve 32 from opening too far. The spring 33 is adjusted so that it is just strong enough to keep the valve seated when there is equal pressure on both sides of the valve. In this way, as soon as sufficient preponderance of pressure exists in the cylinder 11, there is a certainty that the valve 32 will 110 be lifted, and the discharge properly accomplished.

The mechanical arrangement of the valves is of importance also. All of the valve parts for both the intake and the discharge, are supported on a common member, such as the plate 18, and by loosening a relatively few bolts 19, the entire valve structure may easily be removed, repaired, and replaced should occasion demand.

Due to the great certainty of action of both the intake and discharge valves, their large opening in short intervals, and the compact arrangement, a compressor built in accordance with my invention exhibits a 120 125 130

degree of efficiency which materially exceeds that of other types. There is substantially no dead volume in the cylinder chamber, because of the extremely compact 5 intake valve arrangement, and this feature contributes materially to the desirable results which have been obtained.

I claim:

1. In a fluid compressor, a cylinder, a piston reciprocating within the cylinder, a 10 ton reciprocating within the cylinder, a discharge valve structure, and an intake valve structure, comprising a member at the cylinder end and having discharge apertures, a closure within the cylinder for all 15 of the apertures, a flat spring having a cupped edge engaging the closure, and means for fastening the spring near its center, whereby its edge may be free to urge the closure to close the apertures.

2. In a fluid compressor, a cylinder, a piston reciprocating within the cylinder, a plate forming the end wall of the cylinder, said plate having a series of intake apertures, a common closure for all of the apertures, said closure being disposed within 20 the cylinder, and means for urging the closure in a direction to keep the apertures closed, comprising a spring resiliently engaging the closure on a continuous surface 25 which is substantially coextensive with the series of intake apertures.

3. In a fluid compressor, a cylinder, a piston reciprocating within the cylinder, a plate forming the end wall of the cylinder, said plate providing an annularly arranged 35 intake for the piston, a ring-like closure for the intake disposed within the cylinder, and a shallow cup spring urging the closure to closed position, the spring engaging the closure near the edge of the closure, and fastened near its center to the plate.

4. In a fluid compressor, a cylinder, a piston reciprocating within the cylinder, a plate forming the end wall of the cylinder, said plate having a series of intake apertures 45 annularly arranged, a valve closure of ring form for the apertures, means for limiting the opening movement of the closure, and a cup spring urging the closure to closed position, the edge of said cup engaging the ring closure near its outside 50 edge along a substantially continuous annular surface.

5. A valve structure comprising a member having apertures, a common closure for all the apertures, a flat spring having a cupped edge engaging the closure, and means for fastening the spring near its

center, whereby its edge may be free to urge the closure to close the apertures. 60

6. In a valve structure, a member having a series of apertures, a common closure for all of the apertures, and means for urging the closure in a direction to keep the apertures closed, comprising a spring resiliently 65 engaging the closure on a continuous surface which is substantially coextensive with the series of intake apertures.

7. In a valve structure, a member providing an annularly arranged valve opening, a ring-like closure for the intake, and a shallow cup spring urging the closure to closed position; the spring engaging the closure near the edge of the closure, and fastened near its center to the member. 70 75

8. In a valve structure, a member having a series of apertures annularly arranged, a valve closure of ring form for the apertures, means for limiting the opening movement of the closure, and a cup spring urging 80 the closure to closed position, the edge of said cup engaging the ring closure near its outside edge along a substantially continuous annular surface. 85

9. In a discharge valve for a fluid compressor cylinder, means forming a discharge passageway near the end of the cylinder, means forming a wall between the passageway and the end of the cylinder, said means having an annular connection between the 90 passageway and the cylinder, a ring-like closure for said connection, said closure being in the discharge passageway whereby the pressure of the compressed fluid may urge it to closed position, a guide post extending from the wall and around which the closure is disposed, and a helical spring guided by said post for urging the closure to closed position, said spring exerting only 95 a weak force against the closure. 100

10. In a valve structure for a fluid compressor cylinder, a plate having a pair of series of annular apertures, said series being concentric, ring shaped closures for both series, said closures being disposed on opposite sides of the plate, a cup-like spring engaging one of the ring closures, a guide post around which the other ring closure is disposed, means for fastening the guide post, plate, and cup spring together, and a helical spring guided by the post and having its end turn engaging said other ring closure. 105 110

In testimony whereof, I have hereunto set my hand.

DEXTER C. BAKER.
